(57) **CLAIM**

The ornamental design for a utility holder, as shown and described.

DESCRIPTION

FIG. 1 depicts a front perspective view of the utility holder of the invention.

FIG. 2 depicts a bottom plan view of the utility holder of the invention. The top plan view is a mirror image of the bottom plan view

FIG. 3 depicts a front elevation view of the utility holder of the invention. The rear elevation view is a mirror image of the front elevation view.

FIG. 4 depicts a left side view of the utility holder of the invention. The right side view is a mirror image of the left side view.

FIG. 5 depicts a cross-sectional view of the utility holder of the invention along line 5-5 in FIG. 6.

FIG. 6 depicts a front view of the utility holder of the invention in use.

FIG. 7 depicts a perspective view of the utility holder of the invention in use; and,

FIG. 8 depicts an enlarged perspective view of the utility holder of the invention in use.

The broken lines depict environmental structure and are included for the purpose of illustrating only and form no part of the claimed design.

1 Claim, 4 Drawing Sheets
